David William Price

UNITED STATES PATENT OFFICE

106,399

DESIGN FOR A DRESS

David William Price, New York, N. Y.

Application August 12, 1937, Serial No. 71,019

Term of patent 3½ years

To all whom it may concern:

Be it known that I, David William Price, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The central group of stripes comprising a unit at either side of the front zipper opening, terminate in tucks.

I claim:

The ornamental design for a dress, substantially as shown, and described.

DAVID WILLIAM PRICE.
